UNITED STATES PATENT OFFICE.

OTHO M. OTTE, OF JAMESTOWN, NEW YORK.

AUTOMOBILE-LAMP.

1,260,439.

Specification of Letters Patent. Patented Mar. 26, 1918.

Application filed July 17, 1917. Serial No. 180,994.

To all whom it may concern:

Be it known that I, OTHO M. OTTE, a citizen of the United States, residing at the city of Jamestown, in the county of Chautauqua and State of New York, have invented certain new and useful Improvements in Automobiles - Lamps, of which the following, taken in connection with the accompanying drawings, is a specification.

- 10 The invention relates to lamps for vehicles and similar constructions wherein it is desired to project the light for a particular purpose; and the object of the improvement is to provide an oblong parabolic 15 shaped reflector formed of two half paraboloids connected by a flat strip so that the light emitted by the lamp is projected in a single shaft which has greater width than height, the peculiar formation of said parabolic reflector being such that said shaft of 20 light is widened by a flare projection which covers a well defined area as, for example, the width of a roadway, provision being made for protecting the vision of bystanders or passersby by means of a tubular screen 25 in which the concentric tubes are given the oblong shape of the parabolic reflector with the exception that a central tube is cylindrical and provided with a lens therein in 30 spaced relation to the light to thereby project a central shaft of condensed and parallel rays through the wider lighted area; and the invention consists in the novel features and combinations hereinafter set forth and 35 claimed.

In the drawings, Figure 1 is a vertical diametral sectional view of the lamp showing the construction and arrangement of the different parts, the direction of the reflected rays of light being shown by dotted lines and arrow heads. Fig. 2 is a perspective view of the compound parabolic reflector, the front tubular portion of the shell being broken away and the flattened section of the larger reflector being shown in dotted line. Fig. 3 is a diagrammatic sectional representation of the reflected shaft of light showing the broad or oblong shape of the shaft with the central condensed shaft through the same. Fig. 4 is a perspective view of the inner end of the central tube showing the complementary ring reflector on said inner end. Fig. 5 is a diametral sectional view

at line 5—5 in Fig. 6 showing in dotted line the difference between the diametral vertical section shown in Fig. 1 and this diametral horizontal section. Fig. 6 is a front perspective view of the lamp showing by dotted lines the arrangement of the flattened vertical central portions in the vision protecting tubes and the section in the parabolic reflector, as well as the cylindrical central tubes. Fig. 7 is a horizontal sectional view at line 7—7 in Fig. 6, showing the peculiar contraction of the flared rays 65 of reflected light at this point in the construction of the lamp; and Fig. 8 is a horizontal sectional view at line 8—8 in Fig. 6 showing the still further contraction of the rays of light except the central rays through 70 the cylindrical central tubes. Fig. 9 is a diagrammatic view of the flat reflector section showing the direction of the flared rays of light from said section.

Like characters of reference refer to corresponding parts in the several views.

The numeral 10 designates the outer oblong shell or casing of the lamp, which casing is preferably made of thin sheet metal, having openings at each end, the front end 80 of the shell 10 being tubular, in the form of a circle flattened on its upper and under sides or somewhat elliptical and corresponding to the shape and diameter of the larger end of the dome or parabolic reflector. 85

The front end of the shell 10 is closed by means of an oblong glass 11 which is held in place by a metal rim 12, preferably with a rubber gasket 13 beneath the same and between said glass 11 and the spacing ring 14. 90 The inner shell 15 is shaped in the peculiar oblong or flattened form substantially the same as the outer shell 10 and is held in spaced relation thereto at the front end by means of the spacing ring 14 and near the 95 rear end by the spacing ring 16, the outer shell 10 and the inner shell 15 being attached to the spacing rings 14 and 16 in any suitable manner.

The inner shell 15 comprises the oblong 1 or elliptical shaped parabolic or dome-shaped reflector 17 and the front cylindrical portion. The inner surface of the parabolic reflector 17 is polished or coated with a reflecting substance and the oblong tubular or cylindrical front portion of the shell 108

15 is uncoated. The shape of the reflector 17 and the tubular front portion of the shell 15 is that of a circle flattened on its upper and under sides, or it may be more perfectly 5 described as composed of two half paraboloids connected by a flat strip, or as a circle divided diametrically and a rectangular flattened section inserted, which is outlined in Figs. 2 and 6 by dotted lines and 10 designated by the letter Z in the reflector 17, and in the front tubular portion of the shell 15 the flattened portion is outlined by the lines X—X and Y—Y; thus the outer portions, that is, the parts outside of the 15 lines X—X and Y—Y, are the perfect halves of a circle which are separated by the inset flattened parts.

The width of the flattened part Z in the reflector 17 is proportioned to the width of 20 the flare which is desired at the front of the lamp. Thus, as shown in the diagram in Fig. 9, the reflected light from said flattened area of the portion Z forms a cone, the base of which is the desired width of the flared 25 cone of light at the front of the lamp and the apex of said cone is back of said flattened strip Z a distance equal to the distance of the source of light 18 in front of said strip Z. The entire reflector 17 is bisected by a vertical strip inserted between the two halves of the parabolic reflector, 30 said strip having a single curvature and coinciding in contour to the central cross section curvature of said parabolic reflector. 35 It may be superimposed or integral without departing from my invention.

The central portion of the oblong parabolic reflector 17 has an opening 19 therein surrounded by a curved flange 20 into which 40 a smaller parabolic reflector 21 is sprung, being made to fit closely within said curved spring flange 20 which thereby holds the smaller reflector 21 firmly in position upon and so related to the larger parabolic reflector 17 that it closes the small opening in 45 the center of the same.

The two reflectors 17 and 21 are substantially continuous, that is, the shape of the smaller reflector 21 is such that the largest 50 radii of said smaller reflector 21 are less than the shorter radii of the greater reflector 17, the two reflectors being shaped to receive one another in substantially continuous reflecting surfaces. The smaller reflector 21 55 is not usually made in the peculiar flattened or oblong circular form hereinbefore described for the reflector 17, though it may be so made without departing from my invention.

60 An electric lamp 18 furnishes the source of light and is mounted in a suitable lamp holder 22 supported in the center of the small reflector 21 and has the connecting wires 23 leading to the source of electrical 65 energy. The electric lamp 18 or source of

light when mounted in the holder 22 is so placed in relation to the reflectors 17 and 21 that the center of the light is at that point which will best be reflected by the two reflectors in their relation to each other. 70

The casing 10 has an opening in its rear end for the insertion of the smaller reflector 21, which opening is closed by a screw cap 24 thereby providing easy access to the smaller reflector 21 for the adjustment or 75 repair of the lamp 18 and its connections 23.

In order to protect the vision of the bystander or passerby from the dazzling glare of the lamp, a vision protecting screen is provided comprising a plurality of concentric parallel tubes 25 which are shaped in the oblong circular form as described for the front portions of the shells 10 and 15. The parallel tubes 25 are held in spaced relation by radial wires 26 which extend 80 through and are attached to each of said concentric tubes 25 and the assembled concentric tubes 25 are mounted in the tubular front portion of the inner shell 15, the front ends of said tubes being placed a spaced 85 distance from the glass 11 in order to give heat circulation and thence they extend back to the beginning of the parabolic reflector 17. Each of the vision protecting screen tubes 25 has the flattened portion 27, as 90 shown in front elevation in Fig. 6 between the lines X—X and Y—Y. The central tube 28 is preferably cylindrical or round and the holding wires 26 are attached to said central tube 28 so as to hold it firmly in position in the center of the elongated field of light. The round tube 28 preferably has therewithin a second round tube 29 to which the inner ends of the wires 26 are attached.

The round tube 28 has an annular groove 105 30 near its rear end into which is sprung a lens 31 to thereby hold said lens a spaced distance from the source of light 18. The rear end of the tube 28 supports the ring reflector 32 by means of which a portion of 110 the central rays of light are reflected into the smaller reflector 21 and thence through the central tubes 28 and 29, the lens 31 refracting all the direct and reflected rays 115 into parallel lines so that a strong central shaft 33 of light is projected through the lighted area or field, as shown in Fig. 3, thereby brilliantly lighting the special portion of the track upon which the wheels of the vehicle move. 120

I claim as new:—

1. In an automobile lamp, a reflector composed of two half paraboloids connected by flattened parts, and a vision intercepting screen composed of spaced concentric tubes 125 flattened on their upper and lower sides to correspond and extend parallel to the respective flattened parts of the reflector.

2. In an automobile lamp, a reflector composed of two half paraboloids connected by 130

flattened parts, and a vision intercepting screen composed of a central circular tube, a lens in the tube, and spaced concentric tubes surrounding the central tube and being flattened on their upper and lower sides to correspond and extend parallel to the respective flattened parts of the reflector.

3. In an automobile lamp, a reflector composed of two half paraboloids connected by flattened parts, and a vision intercepting screen composed of a central circular tube, a lens in the tube, a second circular tube in said first named tube arranged in front of the lens, and spaced concentric tubes surrounding the central tube and being flattened on their upper and lower sides to correspond and extend parallel to the respective flattened parts of the reflector.

4. An automobile lamp comprising a reflector composed of two half paraboloids connected by flattened parts, a source of light central of said reflectors to reflect the light in parallel lines therefrom, a central light concentrating tube in front of said source of light, a lens mounted in said central tube a spaced distance in front of said source of light, a complementary ring reflector on the inner end of said central tube to aid in reflecting the rays of light through said tube, a vision protecting screen consisting of concentric tubes held in spaced relation around said central tube, said spaced concentric tubes flattened on their upper and under sides in conformity with said com-

5. In a lamp a source of light, a reflector composed of two half paraboloids connected by a flat strip, said strip having a single curvature and coinciding in contour to the central cross section curvature of said parabolic reflector, a vision intercepting screen having flat planes, said strip having a flattened area of width that will allow the reflected light from said strip to form a cone the base of which is the width of the flat plane in the vision intercepting screen and the apex is back of said strip a distance equal to the distance of the source of light in front of said strip.

6. In a lamp, a source of light, a reflector composed of two half paraboloids connected by flattened top and bottom parts, a condensing lens, a circular tube alined with the lens, and a screen surrounding the tube and having flattened top and bottom parts.

7. In a lamp, a source of light, a reflector shaped to provide a wide flat lighted area, vision intercepting means having flat bottom parts, and a lens to project a circular shaft of light in the center of said area.

In testimony whereof I have affixed my signature in the presence of two witnesses.

OTHO M. OTTE.
